(57) **CLAIM**

The ornamental design for a slot clamp assembly, as shown and described.

DESCRIPTION

FIG. 1 is a top perspective view of two slot clamp assemblies in use, clamping a work piece down onto a slotted table. FIG. 2 is a top perspective view of a slot clamp assembly, showing my new design.

FIG. 3 is a side elevation view of FIG. 2.

FIG. 4 is a front elevation view of FIG. 2.

FIG. 5 is a top plan view of FIG. 2; and,

FIG. 6 is a bottom plan view of FIG. 2.

The features shown in broken lines depict environmental structure only and form no part of the claimed design.

1 Claim, 2 Drawing Sheets

FIG. 2

FIG. 3

FIG. 4

FIG. 5

FIG. 6
